HOUSING FOR METAL DETECTOR

Thomas H. Doss, P.O. Box 10563,
Houston, Tex. 77018

Filed Jan. 21, 1969, Ser. No. 15,416

Term of patent 14 years

Int. Cl. D10—99

U.S. Cl. D52—6

FIG. 1 is a front perspective view of a housing for a metal detector, showing a new design;

FIG. 2 is a back perspective view from a point lower than that of FIG. 1 showing the housing for the metal detector; and,

FIG. 3 is a side view of the lower end of the metal detector disclosing the side profile or view thereof.

The staff extending between the upper and lower portions is shown broken away to indicate that its length is indeterminate.

What is claimed is:

The ornamental design for a housing for metal detector, as shown.
